JOHN W. YATES, OF NEW YORK, N. Y.

SASH-PIVOT.

1,218,348.

Specification of Letters Patent. Patented Mar. 6, 1917.

Application filed June 20, 1916. Serial No. 104,648.

To all whom it may concern:

Be it known that I, JOHN W. YATES, a citizen of the United States, residing in the city of New York, borough of Manhattan, county 5 and State of New York, have invented a certain new and useful Sash-Pivot, of which the following is a specification.

This invention is a sash pivot, particularly adapted for use on fireproof windows 10 of warehouses, factories, etc., and embodies, speaking generally, means for mounting the sash for pivotal movement, with which means is associated a latch or detent for automatically limiting the opening movement of the sash to a predetermined angle, where it is held by suitable means, such as a fusible link. When a fire takes place in 15 proximity to such window, the fusible link melts, and, as the angle of inclination of the sash, when open, is such that the line of weight of said sash falls outside of the pivotal connection, the disruption of the fusible link releases the sash and allows it to 20 gravitate into closed position.

25 The mountings for sashes of this type are in the form of two pivots, one at either side of the sash. With one of the pivots is associated the means for normally limiting the movement of the sash to a predetermined 30 angle of inclination, while the other pivot serves purely as a pivot, and generally has no such means associated therewith, as the sash may be readily governed from one of its lateral edges only. The present invention 35 is directed to the pivot which is associated with the means for limiting the opening movement of the sash.

The object of this invention is to improve upon sash pivots of the general character described in order to make them more positive in their operation, stronger in construction, and operable with greater expedition.

In one of its practical forms, the invention 45 embodies a pivot plate adapted to be mounted on one of the side stiles of a sash and provided with an integral, laterally extending pivot pin journaled in a stop plate fixed on the window frame. The stop plate is provided with two shoulders or stops adapted 50 to be engaged by a latch mounted on the pivot plate, for pivotal movement about an axis extending forwardly of the pivot plate and at an oblique angle to the face of said plate. With said latch co-operates a weight 55 which forces the latch into engagement with

the stops of the stop plate in accordance with the manipulations of the sash and latch.

Features of the invention, other than those specified, will be apparent from the herein-after detailed description taken in conjunction with the accompanying drawing.

In the accompanying drawing, I have illustrated one practical embodiment of the invention, but the construction shown therein is to be understood as illustrative, only, and not as defining the limits of the invention.

Figure 1 is a fragmental, vertical section through a window-sash showing the preferred form of the present invention in elevation, said section being taken in the plane 70 of the line 1—1 of Fig. 4, and showing the sash in closed position.

Fig. 2 is a sectional view similar to that shown in Fig. 1, but illustrating the sash in its normally open position for ventilation.

Fig. 3 is a section taken on line 3—3 of Fig. 4, showing the sash in the reversed position to which it may be moved for the purpose of cleaning the outside of the sash pane.

Fig. 4 is a front elevation of the structure 80 as shown in Fig. 1, and

Fig. 5 is a fragmental perspective of the upper portion of the sash plate.

Referring to the drawings, A designates a pivot plate, which is secured by a plurality 85 of bolts or screws *a* to the face of one side stile of a window-sash B. Formed integral with pivot plate A is a horizontal, laterally extending pivot pin C adapted to extend into a journal in the form of a circular hole *c* 90 in a stop plate D positioned at right angles to pivot plate A and secured to the window frame by a plurality of screws *d*. By the co-operation between pivot pin C and the stop plate, the side stile of sash B is mounted for 95 pivotal movement within the frame.

At the upper portion of pivot plate A, and near its lateral edge, said plate is provided with a forwardly extending bracket *a'*, the forward face *a''* of which is vertically inclined, as shown in detail in Fig. 5, so as to lie in a plane in obtuse angular relation to the face of window-sash B. Pivoted to the face *a''* by means of a rivet, bolt or screw *e*, is a latch E, shown in the form of a bell-crank, one arm of which is provided with a nose *e'* and the other arm of which is formed into a weight *e''*.

Formed on the forward edge of stop plate D is a shoulder *f*, the upper face of which is 110

in a plane substantially radial of pivot pin C, as shown more particularly in Figs. 1, 2 and 3, and the plate is recessed, as at f', adjacent said shoulder to render the shoulder 5 more extensive.

The relation of the parts is such that, when sash B is in the closed position shown in Figs. 1 and 4, weight e² of latch E will maintain nose e' of said latch in engagement with the adjacent face of stop plate D, and this relation of the parts will remain the same as long as the sash is in closed position. As the sash is opened, latch E is bodily gyrated, with its nose still in engagement 10 with said face of plate D, until the sash has been inclined to the position in which it is desired to normally maintain the same for ventilating purposes, at which time the nose of the latch has advanced to a point opposite the cut-away or recessed portion f' of the stop plate. When the latch reaches this position, its nose is no longer in engagement with the stop plate and, because of its weighted arm e², is rotated into a position 15 within recess f'. In order to preclude the latch from over-traveling, the lower portion thereof is formed with a heel e³, which, when the nose e' enters the recess of the stop plate, engages with the face of said plate to preclude over-travel of the latch. It will be 20 manifest that, when the nose of the latch is positioned as described, in the recess of the stop plate, its forward face will come into engagement with shoulder f and preclude further pivotal movement of the sash. 25

As an additional precaution against over-travel of the latch, as well as to preclude its travel in the opposite direction to such extent that it would engage with and dent 30 the metal from which fireproof sashes are generally constructed, the back side of the depending arm of the latch is preferably provided with a rib or projection e⁴, which loosely lies between two substantially vertical flanges a⁴, which extend downwardly 35 from the forwardly extending bracket a' and at the lateral edges thereof. The relation between flanges a⁴ and projection or rib e⁴ is such as to allow of the required pivotal movement of the latch for its proper operation, but to preclude over-travel of the latch in either direction. Heel e³ is thus relieved 40 of excess strain, and, at the same time, pivotal movement of the latch in the opposite direction is restricted to such extent that the weighted portion e² will not engage with and dent or scratch the sash. 50

The pivoting of latch E to oscillate, figuratively speaking, in a plane oblique to the 55 plane of the face of the sash, by positioning its pivot e at an obtuse angle to the face of the sash, plays an important part in making the present invention superior to any sash pivot heretofore employed. When the sash 60 is in closed position, face a², on which the

latch is pivotally mounted, lies, in the preferred construction shown in the drawing, in a plane at substantially 45 degrees to the vertical, whereas, when the sash is inclined to its ventilating position shown in Fig. 2, 70 said face is substantially vertical. Accordingly, when the sash is closed, latch E lies on, and is, literally, supported by, face a² so that its weight is not imposed entirely upon pivot e. Moreover, the tendency of 75 weighted arm e² to oscillate the latch is not so great as if the latch were pivoted on a horizontal pivot, and, accordingly, the friction between nose e' and the face of the stop plate, when the sash is opened, will not be 80 so great, with the result that the wearing of the free edge of nose e' is almost entirely obviated. It will be remembered that, when sash pivots of this type are once installed in a building, they are expected to withstand 85 the use of a long term of years, and, where the sashes are opened and closed two or more times every day, the wear on the nose of the latch, while not very much each time, will, after a comparatively short period, be 90 sufficient to impair the maximum efficiency of the latch. Thus, while the face of the stop plate D guides the nose of the latch into engagement with shoulder f, the weighted arm e² of said latch will not be brought to 95 bear with its entire force to swing the latch into the recessed or cut-away portion f' until the sash has substantially reached its predetermined ventilating inclination, at which time pivot e will be substantially horizontal 100 and will allow of the proper swinging operation.

The mounting of the latch as described results in still another, and very important, feature, viz., that it allows of the positioning of shoulder f at a maximum distance from pivot C, the making of this shoulder quite extensive, and also the bringing of said shoulder almost under the pivotal connection between the latch and the pivot 105 plate, as shown more particularly in Fig. 2. A relatively broad expanse of the latch thus lies directly upon the shoulder, when the sash is open as described, and there is an upward thrust on its pivot e, which is 110 transmitted directly to the bracket portion a' of the pivot plate. The leverage thus afforded by the sash pivot of this invention, for withstanding the strains occasioned by the sash when in ventilating position, is 115 thereby considerably in excess of any of the pivots heretofore suggested, and greatly increased strength thereby results.

It will, of course, be understood that the window is maintained in its ventilating position by the usual means, generally in the form of a chain embodying a fusible link, said fusible link being adapted for disruption, upon the application of heat, to release 120 the sash and allow of the automatic closing 125

thereof. The structure of the latch and stop plate D, with which it co-operates, is such that, when the sash is released, upon the disruption of the link, the sash will 5 automatically gravitate into closed position. It will be noted that the fact that nose e' of the latch extends into the recessed or cut-away portion f', will not in the least interfere with the closing movement of the sash, 10 since, as shown in Fig. 3, said nose is beveled or curved so that, when it comes into engagement with the upper edge of said recessed portion, it will be forced into a retracted position. The latch cannot fail 15 to operate as described, since the weight of the sash is so greatly in excess of the weight of the latch, and the oblique pivoting of the latch as described is, moreover, conducive to maximum efficiency in the retracting operation.

As windows of the type with which this invention is adapted for use are often in very inaccessible positions, which preclude them from being washed from the outside, 25 the latch is adapted for movement to allow of the reversing of the sash so that it may be cleaned from the inside of the building. It will be manifest that, when the sash is in the position shown in Fig. 2, with the 30 nose of the latch in engagement with shoulder f, with which it has come into engagement automatically upon the opening of the sash to its ventilating position, it will normally preclude the further pivotal 35 movement of the sash in an opening direction. However, the latch may be grasped in the hand and manually operated to withdraw or retract its nose from the recessed portion f' and out of engagement with 40 shoulder f. When this has been accomplished, there is nothing to preclude the further rotation of the sash, so that it is free to move into the reversed position shown in Fig. 3. To preclude over-travel of the sash, a 45 projection d' is formed on the stop plate, in the path of nose e', and said stop is so positioned that, after the sash has been reversed to a predetermined extent, the nose of the latch engages with projection d', 50 which precludes further reversing movement of the sash. When the sash is in reversed position, it may be readily cleaned from the inside, and, after the cleaning operation, it may be again rotated to its closed position, 55 at which time the latch will automatically assume its operative position, shown in Figs. 1 and 4.

Having thus fully described the invention, what I claim as new, and desire to secure by Letters Patent, is:

1. A sash pivot embodying a pivot plate, provided with a portion having an inclined surface, and which pivot plate is adapted to be mounted on a sash, a horizontally positioned pivot pin fixed on said pivot plate,

a stop plate adapted to be secured on a window frame and provided with an aperture into which a pivot pin extends, a shoulder on the stop plate and a latch pivotally mounted on the inclined surface of the pivot 70 plate and adapted to engage with the shoulder on the stop plate, whereby said latch is pivoted for oscillation on an axis extending obliquely to the face of the sash on which the pivot plate is mounted.

2. A sash pivot embodying a pivot plate, provided with a portion having an inclined surface, and which pivot plate is adapted to be mounted on a sash, a horizontally positioned pivot pin fixed on said pivot plate, 80 a stop plate adapted to be secured on a window frame and provided with an aperture into which the pivot pin extends, a shoulder on the stop plate and a latch pivotally mounted on the inclined surface of the pivot 85 plate and adapted to engage with the shoulder on the stop plate, whereby said latch is pivoted for oscillation on an axis extending obliquely to the face of the sash on which the pivot plate is mounted, said latch 90 being weighted whereby a portion thereof is maintained in engagement with the stop plate during the opening movement of the sash for the purpose of guiding said latch into engagement with said shoulder.

3. A sash pivot embodying a stop plate adapted to be mounted on a window frame and provided with an aperture, a shoulder on said stop plate, a pivot plate adapted to be mounted on the sash within the window frame, a pivot pin fixed on said pivot plate and extending into the aperture in the stop plate for pivotally mounting the sash relative to the window frame, a vertically inclined surface at the upper portion of said 100 pivot plate, a latch pivoted to said surface with the axis of pivotal movement of said latch in oblique relation to the face of the sash, and means for maintaining a portion of the latch in engagement with the stop 105 plate during the operation of tilting the sash, said means being also operable to shift the latch into co-operative relation with the shoulder of the stop plate after the sash has been tilted to a predetermined extent.

4. A sash pivot embodying a stop plate adapted to be mounted on a window frame and provided with an aperture, a shoulder on said stop plate, a pivot plate adapted to be mounted on the sash within the window 110 frame, a pivot pin fixed on said pivot plate and extending into the aperture in the stop plate for pivotally mounting the sash relative to the window frame, a vertically inclined surface at the upper portion of said 115 pivot plate, a latch pivoted intermediate its ends to said surface with the axis of pivotal movement of said latch in oblique relation to the face of the sash, and means, co-operating with one arm of the latch, for main- 120

125

taining the other arm in engagement with the stop plate during the operation of tilting the sash, said means being also operable to shift the latch into coöperative relation with the shoulder of the stop plate after the sash has been tilted to a predetermined extent.

5. A sash pivot embodying a stop plate adapted to be mounted on a window frame and provided with an aperture, a shoulder on said stop plate, a pivot plate adapted to be mounted on the sash within the window frame, a pivot pin fixed on said pivot plate and extending into the aperture in the stop plate for pivotally mounting the sash relative to the window frame, a vertically inclined surface at the upper portion of said pivot plate, a latch pivoted to said surface with the axis of pivotal movement of said latch in oblique relation to the face of the sash, means for maintaining a portion of the latch in engagement with the stop plate during the operation of tilting the sash, said means being also operable to shift the latch into coöperative relation with the shoulder of the stop plate after the sash has been tilted to a predetermined extent, and said latch being manually shiftable from a position wherein it is in engagement with the shoulder to allow of further pivotal movement of the sash, and means for limiting such further pivotal movement to a predetermined maximum.

6. A sash pivot embodying a stop plate adapted to be mounted on a window frame and provided with an aperture, a shoulder on said stop plate, a pivot plate adapted to be mounted on the sash within the window frame, a pivot pin fixed on said pivot plate and extending into the aperture in the stop plate for pivotally mounting the sash relative to the window frame, a vertically inclined surface at the upper portion of said pivot plate, a latch pivoted intermediate its ends to said surface with the axis of pivotal movement of said latch in oblique relation to the face of the sash, means coöoperating with one arm of the latch for maintaining the other arm in engagement with the stop plate during the operation of tilting the sash, said means being also operable to shift the latch into coöperative relation with the shoulder of the stop plate after the sash has been tilted to a predetermined extent, and said latch being thereafter manually shiftable to a position free from engagement with the shoulder of the stop plate to allow of the reversal of the sash, and a projection on the stop plate and in the path of the

latch for limiting the reversing movement 60 of the sash.

7. A sash pivot embodying two plates pivoted together, one of which is adapted to be secured to a window frame and the other to a sash to pivotally support the same within the frame, a shoulder on the frame plate, and a coöperating latch on the sash plate, the sash plate being provided with a portion having an inclined surface to which said latch is pivoted for oscillation on an axis 70 extending obliquely from the face of the sash.

8. In a device of the class described, the combination of a latch adapted to be pivotally mounted on an inclined surface on a 75 window sash for oscillation on an axis extending obliquely from the face of the sash, and a shoulder secured to the frame in which the sash is mounted and adapted to engage with the latch, when the sash has been 80 opened to a predetermined extent, to normally preclude further movement of the sash in an opening direction.

9. In a device of the class described, the combination of a latch adapted to be pivotally mounted on an inclined surface on a window sash for oscillation on an axis extending obliquely from the face of the sash, and a shoulder secured to the frame in which the sash is mounted and adapted to 90 engage with the latch, when the sash has been opened to a predetermined extent, to normally preclude further movement of the sash in an opening direction, said latch being manually shiftable from engagement 95 with the shoulder to allow of the further pivotal movement of the window into a reversed position.

10. A sash pivot embodying two plates, one of which is mounted on a sash and the other of which is mounted on a window-frame, said plates being pivoted together for pivotally mounting the sash within the frame, a shoulder on the frame plate, a co-operating latch pivoted to the sash plate, 100 said latch being weighted to swing into engagement with the shoulder when the window has been opened a predetermined extent, the latch being pivoted for oscillation about an axis positioned obliquely to the 105 face of the sash, and a projection on the latch extending between two limiting projections on the sash plate whereby over-travel of the latch in either direction is precluded.

In testimony whereof I have signed my name to this specification.

JOHN W. YATES.
